ROTARY ENGINE

Anton Metzler, Rochester, N. Y., assignor of one-half to Anthony Metzler, Rochester, N. Y.

Application May 15, 1933, Serial No. 671,196

10 Claims. (Cl. 121—56)

The object of this invention is to provide a rotary motor which is driven by water or steam, etc., in which the central axis or tube through which the power is supplied remains stationary, 5 and the motor housing rotates around it, being driven by the circulation of the water or steam from the central axis into the motor housing, and then out again through the central axis.

Another object of the invention is to provide 10 a stationary gear mounted on a stationary inside casing, and to surround this with a rotating housing provided with a plurality of vanes which are turned by pinions which mesh with and travel around the stationary gear on the stationary casing.

Another object is to provide a rotary vane turning 15 around a stationary core that is fastened rigidly to the outside rotating housing.

These and other objects of the invention will 20 be illustrated in the drawings, described in the specification, and pointed out in the claims at the end thereof.

In the drawings:

Figure 1 is a vertical section through my rotary 25 motor, the section being taken on the line 1x—1x of Figure 3.

Figure 2 is a vertical section through the end 30 of my rotary motor, the section being taken on the line 2x—2x of Figure 3.

Figure 3 is a vertical longitudinal section 35 through my rotary motor, the section being taken on the line 3x—3x of Figure 1.

Figure 4 is a side elevation of one of the rotary vanes.

Figure 5 is an end elevation of the vane and 40 pinion of Figure 4 viewed from the left.

Figure 6 is a side elevation of one of the stationary cores around which the vane rotates.

Figure 7 is an end elevation of the core shown 45 in Figure 6, viewed from the left.

Figure 8 is a section on the horizontal line 8x—8x of Figure 3, looking up in the direction 50 of the arrow, the section being partly broken away at the left on or near the vertical line 4x—8x of Figure 3.

Figure 9 is a sectional elevation on the line 9x—9x of Figure 3 on a smaller scale looking in the direction of the arrow.

Figure 10 is a vertical section taken through 55 the apparatus shown in Figure 1 on the line 10x—10x of Figure 1.

Figure 11 is a side elevation of the rotary housing.

Figure 12 is a sectional view on a smaller scale 55 through one of the stationary arms of the sta-

tionary casing the section being taken on the line 12x—12x of Figure 1 showing the ducts through which oil is distributed.

In the drawings like reference numerals indicate like parts.

In the drawings reference numeral 1 indicates 10 the hollow stationary casing or support having a web 2 extending diametrically across it. On this web are fastened the blades or arms 3 and 4 shown in section in Figure 1.

The stationary casing is contained in a rotating 15 housing 5 shown in Figures 1, 3, and 10. This rotating housing is a cylindrical shell provided with seven shells 6, 7, 8, 9, 10, 11 and 12, which are formed integral with the rotating 15 housing. Each of these shells is cored out to form passages for the steam or water and to receive the rotating vane or vane 13 shown in Figure 4. Seven of these rotating vanes are 20 provided, one in each shell. These rotating 25 vanes are all alike, and on the end are provided with a pinion 14, all of which mesh with a stationary gear 15 provided on the end of the inside stationary casing. As the outside housing 20 rotates, the pinions 14, of which seven are shown in Figure 2, are in engagement with the stationary gear 15 and turn on their own axes, being turned by their engagement with the stationary gear, around which they move with the 30 rotating housing. Each of the pinions 14 is provided with eight teeth, and the gear 15 is provided with 32 teeth so that the ratio between the pinions and the large gear 15 is one to four, and this will cause each of the vanes 13 to 35 make four complete revolutions as the outside housing turns through one revolution.

As shown in Figure 3, 20 is an entrance port in stationary member 20' through which steam or water under pressure enters the rotary motor, and in turn passes into the port 21 in the 40 casing 1. The driving fluid, steam or water, passes out through the port 22 in casing 1 and through the port 23 in stationary members 20''. It will be understood that the ports 20 and 23 are stationary and will connect with 45 suitable corresponding ports in casing 1 framework of the automobile. The members 20' and 20'' shown at the right of Figure 3 are swivelly connected to the stationary casing 1 in which the ports 21 and 22 are formed, and the ports in the members are in alignment with the ports in the stationary casing 1 on a central axis that corresponds with the section line 9x—9x of Figure 3, it being understood that the section line 9x—9x on Figure 3 represents a vertical axis 55

on which all of the parts at the left of Figure 3 can swing on a horizontal plane.

It will also be understood that the parts at the left of Figure 3 serve as a support on which 5 the hub of a wheel will be fastened, and which wheel will rotate with the outer housing and will be driven thereby in the manner now described.

As shown in Figure 9 the driving fluid enters 10 from the bottom, through the ports 20 and 21, and passes around through the openings 24 in the inside stationary casing and through the ports 25, 25 into the segmental opening between the stationary inside casing and the rotating out- 15 side housing. As shown near the top of Figure 1, the core 30 slides past the end of the arm 4 and its valve leaves open the ports on either side of it. While this occurs, high pressure steam can enter the annular space ahead of it and ex- 20 haust steam can pass out from the annular space behind it. The steam presses against the valve ahead of it, which has closed the annular space, and causes the rotation of the outside housing. Each valve in turn closes this annular 25 space while the valve behind it is admitting steam thereto. Each of the valves will turn through one complete revolution in going one quarter of the way around the circle shown in Figure 1 and will go through a half revolution by the time it has 30 advanced forty-five degrees. As fast as the valves close, the steam is trapped between the closing valve and the valve ahead of it and this steam remains idle until the valve ahead reaches the exhaust port or the arm 3, at which time the 35 valve takes the position shown near the top of Figure 1, permitting the exhaust steam to pass out on one side of the arm 3 and high pressure steam to pass into the annular space on the other side of the arm 3, it being understood that in 40 each case the steam flows in the direction shown by the arrows in Figure 1.

It will be seen in Figure 1 that the arms 3 and 4 divide the annular passageway into two segments, and when the vanes come to these arms 45 it is necessary for the vanes to pass over these arms without making mechanical or obstructing contact therewith. The gearing by which the vanes are rotated is so adjusted that the vane is contained in the shell at the time the vane is 50 passing over these arms, and the cores 30 slide past the ends of the arms 3 and 4, making close sliding contact therewith so that there is little or no leakage at that point. The outer end of each arm 3 and 4 is flared out so that it more 55 than spans the opening through which the vane rotates, thus closing the opening so that no leakage can occur through the opening.

In each shell a passageway 31 is provided, through which suitable lubricating material is 60 fed to the vane so that it will be properly lubricated while it rotates.

By inspection of Figures 3 and 10 it will be seen that the stationary casing 1 includes the inlet port 21, and the outlet port 22, the cylinder 36, the boss 37, and the stud 38a, all of which are 65 integral and stationary.

The housing 5 rotates and with it are joined other parts that may be described as follows. An 70 annular ball race 38 is provided, which rotates 75 against a similar stationary ball race 39 provided on the housing 1. An annular head 40 is provided, which is separated from the annular ball race 38 by a spacing ring 41. The spacing ring and the annular head 40 are held together by a 75 ring 42 having a female threaded end with which

it engages the male thread on the ball race 38, and having a shouldered rim 43, which engages with the annular head 40.

The stationary cores 30 are assembled on the annular head 40. Each of these cores is provided 5 on the end with a stud 44, which passes through an opening in the annular head and is fastened thereon by a washer 45 and nut 46.

The cores are first fastened to the annular head 40 and then the ball race 38 is placed in proper 10 position with the spacing ring 41 between the race and the head 40. The ring 42 is then slipped over the assembly, and makes threaded engagement with the rim of the ball race 38. The parts 15 so assembled can then be slipped over the cylinder 36.

At the end of the rotating housing 5 is provided 20 an annular head 47, which is perforated at suitable intervals 48a to receive the studs 48 on the vanes 13, which extend through it. A 25 head 49 is provided having a perforation therein that goes over each of the studs 48.

A pinion 14 is then placed on the stud 48 and keyed thereon, so that the pinion and vane 13 25 rotate together.

As will be seen at the top of Figure 3, the head 40 is countersunk as shown at 40a to receive the end of the stationary core 30 and the end of the rotating vane 13.

The gear 15 is fastened to the boss 37 by four 30 screws 50 as shown in Figure 2. This gear remains stationary with the boss while the pinions 14 rotate around it and are turned thereby. On the end of the boss 37 is provided a cap 51, which is provided with a ball race 52, which makes contact with a similar ball race 52a on the boss 37. The cap 51 has a flange 51a thereon which makes close contact with the head 47, and rotates there- 35 with together with the head 38 and the parts that are held therebetween, which includes the hous- 40 ing 5, and the seven shells, and the seven vanes and the seven cores.

It will be understood that my motor, which is shown in Figures 1, 2 and 3, is adapted to carry the front wheel of a car and is also adapted to be 45 swivelly supported on the frame of a car on a vertical axis so that the wheel can be turned for steering.

To provide for the turning of a front wheel, I provide the skew rack 55 shown in horizontal 50 section in Figure 8, which meshes with the skew gear or pinion 56 shown in Figure 3, which is driven by the steering post 56'.

To provide lubrication, I provide in the casing 1 two oil holes or ducts 57, 57, which may be connected to oil cups not shown. The head 38 at suitable intervals is provided with oil ducts 58, and rotates in a channel 38' in the head 1. As the head 38 rotates on casing 1 carrying ducts 58 with it the ducts 57, they will take oil therefrom, 60 which will be fed into the shell and will serve to lubricate the rotating vanes. At two or more places I provide ducts 59 shown at the bottom of Figure 10, which extend from the head 40 to the head 47, and convey the oil from the right 65 hand side of the assembly shown in Figure 3 to the left hand side, so that oil will be fed to all the moving parts and lubrication will be secured thereby.

As shown in Figure 7, the stationary core 30 70 is provided with an oil duct 60 running across the end thereof and oil ducts 61 on each side thereof. An oil duct 30a shown in Figure 1 runs through the core. These convey the oil from one end of the assembly to the other.

In Figure 12, I have shown a section of the end of one of the arms 3 and 4. As shown, the arm is bored to form the ducts 64 running across the arm, and the lateral ducts 65 extending outward therefrom, and the ducts 66 branching off of the two end ducts 65.

As shown in Figures 1, 2 and 10, I provide seven bolts 67, which are used to tie together the heads 40 and 47.

10 The outer ends of the arms 3 and 4 are connected to the casing 1 by webs 68, 69 which are shown in side elevation in Figure 1 and end elevation in Figures 3 and 10. These webs strengthen the ends of the arms and hold them in place rigidly with reference to the stationary casing and still leave ample room for the flow of steam past them through the ports 25 and 26.

Steam enters through the entrance port 20 and passes into the port 21, and from there into the openings 25 or chambers 24, 24. From these chambers it passes out through the openings 25, 25, indicated by the arrows, into the annular space surrounding the inside stationary casing. The steam or water acts against the vanes 13 and 25 drives the outside housing in the direction indicated by the arrow. As the housing rotates, the vane finally opens to permit the steam or water to escape, through the ports 26 and 27, into the exhaust passageways 28, 28, along which it travels to the exhaust ports 22 and 23. While the outside housing rotates, the vanes 13 are rotated in synchronism therewith, so that the vanes are in the correct position to pass over the blades or arms 3 or 4 and hold the steam or water while it passes from chambers 24, 24 into the annular space surrounding the casing 1. In this way the rotating housing is driven by the steam or water and rotates on the stationary casing within it.

I claim:

40 1. A rotary motor, a stationary casing, a rotating housing around it with an annular space between the casing and housing, the stationary casing being hollow, webs and blades dividing it into passageways, said blades in said casing projecting diametrically from said stationary casing and making contact with the rotary housing, said stationary casing being cut away on each side of said blades, webs by which the stationary casing is connected to said blades, and forming ports 50 which lead into and out of the stationary casing.

2. In a rotary motor, the combination of a stationary cylindrical casing cut away at two diametrically opposite places, leaving openings in the periphery thereof, blades extending radially through said openings, webs connecting said blades to the periphery of said stationary casing, leaving ports between said webs.

3. In a rotary motor, the combination of members having an inlet and an outlet port, a non-rotating casing swivelly mounted between them, and having inlet and outlet ports therein engaging with the ports above mentioned, a segmental skew gear concentric with the axis of said swivel, means engaging with said segmental skew gear 65 for swinging said casing on its axis.

4. In a rotary motor, the combination of members having an inlet and an outlet port, a non-rotating casing swivelly mounted between them, and having inlet and outlet ports therein engaging with the ports above mentioned, a housing 70 mounted to rotate around the non-rotating casing, with an annular space between them, vanes in said rotating housing that alternately close and open the annular space between the casing and housing, ball bearings between said casing

and housing, permitting the outer housing to rotate on the inner casing.

5. In a rotary engine, the combination of a non-rotating cylindrical casing, a cylindrical housing rotating around it, said cylindrical housing having at one end a ball race, an annular head, a spacing ring separating them, and a ring having a flange on one end and a thread on the other end to hold the ball race and the annular head together and suitably spaced apart by the 10 spacing ring.

6. In a rotary engine, the combination of a non-rotating cylindrical casing, a cylindrical housing rotating around it, said cylindrical housing having at one end a ball race, an annular head, 15 a spacing ring separating them, and a ring having a flange on one end and a thread on the other end to hold the ball race and the annular head together and suitably spaced apart by the spacing ring, stationary cores extending outwardly from 20 said annular head, each of said cores having a threaded end extending through said head into the open space between the head and the ball race, a nut for clamping each of said cores on said head.

7. In a rotary motor, the combination of a stationary cylindrical casing divided diametrically by a web, said casing being cut away at two places diametrically opposite each other and intermediate the ends of said web and forming 30 openings along the periphery thereof, blades extending radially through said openings, webs connecting said blades to the periphery of the stationary casing leaving ports between said webs, said casing being divided thereby into four passageways through two of which the steam can be admitted and through the other two of which the steam can be exhausted.

8. In a rotary engine, the combination of a stationary cylindrical casing, a cylindrical housing rotating around it, with an annular clearance space between them, annular heads at each end of said rotating housing, cores extending outwardly from one of said heads toward the other, each of said cores having a threaded end extending through said head, a vane having an end extending through the other head with a nut thereon, means for causing said vanes to rotate around said stationary cores.

9. In a rotary engine, the combination of a stationary cylindrical casing, a cylindrical housing rotating around it, with an annular clearance space between them, annular heads at each end of said rotating housing, cores extending outwardly from one of said heads toward the other, 55 each of said cores having a threaded end extending through said head, a vane having an end extending through the other head with a nut thereon, means for causing said vanes to rotate around said stationary cores, tie rods connecting said 60 annular heads together.

10. In a rotary engine, the combination of a non-rotating cylindrical casing, a cylindrical housing rotating around it, with an annular space between them, said cylindrical housing having 65 an annular head at each end, cylindrical members comprising shells spacing said heads apart, stationary cores in said shells mounted on one of said annular heads, vanes mounted to rotate in the other annular head, each of said vanes being 70 adapted to rotate around the stationary cores and into the annular space between the casing and housing, said stationary casing having a web and blade by which it is divided into four passageways and having blades therein extending 75

across said space and into contact with the rotating housing, said stationary casing having a port on each side of said blades connecting the annular space with the passageways in said stationary casing, two of said passageways being adapted to admit steam into the annular space

between the casing and housing to drive the rotating housing, and the other two passageways being adapted to exhaust the steam from said annular space.

ANTON METZLER. 5
